UNITED STATES PATENT OFFICE.

AUGUSTUS B. COBURN, OF ROSEDALE, KANSAS.

DEVICE FOR FASTENING SAW-CLAMPS, &c., TO WORK-BENCHES.

SPECIFICATION forming part of Letters Patent No. 289,227, dated November 27, 1883.

Application filed April 3, 1883. (No model.)

To all whom it may concern:

Be it known that I, AUGUSTUS B. COBURN, of Rosedale, Wyandotte county, Kansas, have invented a new and Improved Attaching Device for Saw-Clamps and other Tools, of which 5 the following is a full, clear, and exact description.

My invention consists of an improved clamp device for attaching saw-clamps, vises, 10 and other tools to the corners of work-benches, timbers, and other supports, the said clamp device being a block capable of sliding in inclined ways in the arm or bracket that rests on the bench, and a lever to draw it forward and downward to force pins or studs of the 15 block into the wood, and at the same time to force other stud-pins of the tool into the side of the bench, making a simple and efficient attaching device, easily and quickly operated 20 by a lever for connecting or disconnecting it, all as hereinafter fully described.

Reference is to be had to the accompanying drawings, forming part of this specification, in which similar letters of reference indicate 25 corresponding parts in both figures.

Figure 1 is a perspective view of a saw-clamp with my improved attaching device, and Fig. 2 is a side elevation of the saw-clamp and end elevation of a portion of the bench.

30 A is a saw-clamp provided with a stationary jaw, B, attached to the bar e, and a removable jaw, C, attached to the upper end of a lever, D, which is pivoted at e² to the arm e¹. The lower end of the lever D is bent upward to form a hook, and is engaged by a pin on a lever, E, pivoted to the part e³, for locking the jaws closed or open, about all of which there is nothing new. a is a block arranged 35 to slide in inclined ways (shown by dotted lines b, Fig. 2, and partly in full lines, Fig. 1) of arms c of a saw-clamp projecting back over the top of the bench d from the bar or frame e, that is to be secured to the side f of the bench or other support to which the saw-clamp is to be attached, the said ways being 40

so pitched that the block will descend when drawn forward and force stud-pins g, fitted in it, into the top of the bench, and for so moving it I connect it with an elbow-lever, h, so pivoted to the frame at i that down or back pressure on the lever will shift the block forward and engage the pins. The lever also serves 50 as a holding device to keep the block in place after being secured by swinging pivot-joint j, by which the rod k is connected to or below 55 the line of the pivot i, thus avoiding the necessity of using any special fastening for the lever. The bar e is also armed with stud-pins l, which are at the same time forced into the 60 side of the bench, making a simple and efficient means of connecting a saw-clamp to the bench, which may be as readily disconnected by raising the lever to thrust out the stud-pins. I propose to fit these stud-pins to screw into 65 their places, so that they may be readily set in as the points wear away, or be taken out for renewal when worn too short.

While I have shown my improvement applied to a saw-clamp, yet it is evident that it is equally applicable to small vises and other 70 tools.

Having thus described my invention, I claim as new and desire to secure by Letters Patent—

1. The combination, with a saw-clamp or other tool provided with horizontal arms having inclined ways, of a block provided with pins sliding in said ways, and an elbow-lever connected to said sliding block, substantially 75 as herein shown and described.

2. The combination, with the saw-clamp A, provided with the arms c, having inclined ways, and the pins l, of the sliding block a, provided with pins g, the connecting-rod k, and the elbow-lever h, substantially as herein shown and described. 80

AUGUSTUS B. COBURN.
